UNITED STATES PATENT OFFICE

HAROLD EMERSON CLARKE, OF WEST SOMERVILLE, MASSACHUSETTS

HINGED LAST

Application filed January 24, 1930. Serial No. 423,205.

My invention relates to hinged lasts and has for its object to provide in a hinged last having a common form of knuckle joint, an improved hinge or linkage means which will be strong, simple and easily manufactured.

My device may be best understood by reference to the accompanying drawing in which

Fig. 1 is a side view of my last in an extended position and partly broken away to show the hinge or linkage means for holding the toe and heel portions together.

Fig. 2 is a side view of my last, similarly broken away, showing the last in a collapsed position.

Fig. 3 is a side view of the hollow pin which is embraced by one end of the connecting link.

Fig. 4 is a vertical cross-section on line 4—4 of Fig. 3.

Referring now more specifically to the drawing, 1 is the toe part of the last which part is provided with an integral boss or knuckle joint 2 of common construction provided with a cylindrical surface 3 which fits 25 into a cylindrical cavity in the heel part 4. Oppositely disposed slots 5 and 6 in the toe and heel parts of the last permit the insertion of a straight metallic link 7, the opposite ends of which are provided with round holes 30 through which pass cylindrical pins 8 and 9 which are mounted in holes placed respectively in the toe and in the heel parts of the last. The holes within which the pins 8 and 9 are mounted are so placed that when the

last is in the extended position, as shown in Fig. 1, a line connecting their axes will lie slightly below the axis of the cylindrical surface 3. Hence, the distance between the axes of the pins when the last is in the extended position is slightly less than the distance must be when either end of the last is elevated so that the said line passes through the axis of the cylindrical surface 3. To permit this relative displacement of the axes of pins 45 8 and 9, it has been the practice to provide

a stretchable or resilient curved link in place of my straight and non-stretchable link 7. To compensate for the non-stretchability of my link 7, I have made the pin 9 hollow or tubular and so thin that it may be slightly 50 distorted, or reduced in diameter, by the stress of the link when the last is being broken. Although I have shown the pin 9 as hollow and the pin 8 as solid, it will be readily understood that these differences of structure may 55 be reversed, or both pins may be hollow.

The pin 9 is preferably made slightly tapered at one end, as shown in Fig. 3, for convenience in inserting the pin within the link.

I am aware that the use of a tubular pin has been previously suggested in the form of a pin provided with a slot so that the wall of the tubular pin is in effect a curved spring, but such a pin is expensive to make and must be accurately positioned in the last and is apt to partially rotate accidentally in the course of the use of the last, so that the slot comes into such a position that the spring effect is lost. I have discovered that these very 70 disadvantageous features of a slotted pin may be wholly and very advantageously eliminated by the use of a pin having a continuous, unbroken cylindrical wall, provided that wall is made so thin as to be capable of slight distortion under the stress of the pressure of the link when the last is being broken. A thickness of about one-thirtieth of an inch in the steel stock employed in the tubular pin will give the desired result.

By the employment of my device the link 7 may be very easily and cheaply made without employing a hardened spring steel and since the hollow pin, unlike the curved spring link, affords a considerable initial resistance to distortion, my last holds the extended position very strongly and will not sag in the middle when in the inverted position in which it is used.

Having thus fully described my invention, what I claim is:

- 5 A last having a toe part and a heel part arranged to turn about a common center, a pair of pins, one of which is transversely mounted in each of said parts, on a line offset from said common center, one of which pins is tubular, and a straight non-resilient link connecting said pins, said pins being so supported in the last parts as to prevent longitudinal flexing of the pins away from their normal axes, and said tubular pin having normally a continuous unbroken cylindrical wall so thin as to permit the distortion thereof 15 when the last is moved to open and closed positions.
